Olaf Hettlesaeter INVENTOR

G. J. DeWitt BY ATTORNEY.

UNITED STATES PATENT OFFICE.

OLAF HETLESAETER, OF MILWAUKEE, WISCONSIN, ASSIGNOR TO ALLIS-CHALMERS COMPANY, OF MILWAUKEE, WISCONSIN, A CORPORATION OF NEW JERSEY.

STEAM-SHOVEL A-FRAME AND CONNECTION.

No. 875,431.

Specification of Letters Patent.

Patented Dec. 31, 1907.

Application filed September 15, 1905. Serial No. 278,563.

To all whom it may concern:

Be it known that I, OLAF HETLESAETER, a citizen of the United States, residing at Milwaukee, in the county of Milwaukee and

5 State of Wisconsin, have invented certain new and useful Improvements in Steam-Shovel A-Frames and Connections, of which the following is a specification.

This invention relates to certain improvements in a laterally stiffening member supporting guys for an over-hanging arm or boom.

More particularly applied to excavators, this feature is termed an "A-frame," and is 15 in the structure disclosed a steel forging.

By my improvements I produce a strong structure having a neat and compact connection for the guys, which is not liable to work loose.

20 In the drawings,—Figure 1 is a front elevation partly broken away, of my improved A-frame with saddle or cap therefor; Fig. 2 is a side elevation thereof; Fig. 3 is a rear elevation of the guy connection or saddle; 25 and Fig. 4 is a side elevation of a swingably mounted over-hanging arm for an excavator or crane, showing how my A-frame is applied thereto.

The one-piece member 1 has the spaced 30 legs serving to laterally stiffen the guys which are attached to the connection 2 at the bent portion of this one-piece A-frame. As there is not proportionally as great a strain on the frame at the bend, this portion is reduced to facilitate bending and thus the cost 35 of manufacture is reduced.

Bolts 3 securely hold the saddle 2 in position on A-frame 1, the holes being bored in the A-frame after the parts are assembled to 40 insure a more accurate fit. This connection or saddle 2 has lugs 4 projecting from one side to which the guys may be attached. This saddle 2 also has a continuous recess 5 in its

under side which receives the reduced bent portion of the A-frame 1. The back guys 6 45 engage the lugs 4 while the boom guys 7 connect the saddle 2 with the swingable over-hanging arm or boom 8.

Having thus described my invention, what I claim and desire to secure by Letters Patent 50 is,—

1. A one-piece A-frame having a reduced portion at the bend.

2. A one-piece A-frame having a reduced portion at the bend, and a saddle having a 55 continuous recess for the A-frame.

3. The combination of a support, an A-frame on the support, a saddle formed with a single recess for reception of the A-frame apex, and guys connecting to the saddle for 60 staying the A-frame.

4. The combination of a support, a one-piece A-frame on the support, a saddle formed with a continuous recess into which the apex of the A-frame is housed, and guys 65 connecting to the saddle for staying the A-frame.

5. The combination of a support, a one-piece A-frame on the support and having a reduced portion at the apex, a saddle on the 70 A-frame at the reduced portion, a boom on the support, and guys for staying the boom and A-frame.

6. The combination of an A-frame bent to form an apex and having a reduced portion 75 at the bend, and a saddle attached to the A-frame at the reduced portion.

7. A forged one-piece A-frame having a reduced portion at the forged apex.

In testimony whereof I affix my signature 80 in presence of two witnesses.

OLAF HETLESAETER.
